UNITED STATES PATENT OFFICE.

MARTIN FEYBUSCH, OF NEW YORK, N. Y., AND PAUL W. FLEISCHER, OF WEEHAWKEN, NEW JERSEY, ASSIGNEES TO NEW JERSEY MACHINE CORPORATION, OF HOBOKEN, NEW JERSEY, A CORPORATION OF NEW JERSEY.

MACHINE FOR WRAPPING BOXES.

Application filed October 17, 1921. Serial No. 508,356.

To all whom it may concern:

Be it known that we, MARTIN FEYBUSCH, a citizen of the United States, and resident of the borough of Manhattan, city, county, and State of New York, and PAUL W. FLEISCHER, a citizen of the United States, and resident of Weehawken, in the county of Hudson and State of New Jersey, have jointly invented certain new and useful Improvements in Machines for Wrapping Boxes, of which the following is a specification.

In the manufacture of boxes, and particularly of boxes made of pasteboard and similar materials, it is customary, in a certain type of box to wrap a single or a compound strip of paper or like flexible material around the body of the box, or the cover thereof, said strip being provided with a coating of paste or other adhesive substance on the side engaging the box part, and projecting therefrom for the purpose of forming edge portions to be bent or folded against the box part. Our present invention relates to a machine of the general type just set forth, and has for its object to provide an increased certainty of operation, so that the machine will perform its work accurately, and that the loss through breakage of jammed box parts will be reduced or eliminated.

A satisfactory embodiment of our invention, as we prefer to use it in practice, is illustrated by the accompanying drawings, in which Figs. 1 and 2 are side elevations of a part of the machine, with parts in section, said two views showing different positions; Fig. 3 is a partial end elevation, showing principally the bottom folders and a box retainer; Fig. 4 is an end view of the box and its carrier or holder; Fig. 5 is a detail elevation, with parts in section, of the cam mechanism for operating the box retainer; Fig. 6 is an elevation, with parts in section, showing chiefly the top folders, the paper pressers, and the box-receiving die; Fig. 7 is a top view showing the parts of Fig. 6 in a different position, partly in section on the line 7—7 of Fig. 6; Fig. 8 is a horizontal section substantially on line 8—8 of Fig. 6, but showing the parts in the same position as in Fig. 7; Fig. 9 is a de-

tail horizontal section of the box, die, and two of the top folders, in a position intermediate between Figs. 6 and 7; Fig. 10 is a section on line 10—10 of Fig. 4; Fig. 11 shows the box in the wrapping position; Fig. 12 is a partial section similar to Figs. 8 and 9, but showing the parts in the same position as Fig. 6; Figs. 13 and 14 are sections on lines 13—13 of Fig. 2 and 14—14 of Fig. 13 respectively; Figs. 15 and 16 are elevations of two strips forming part of the machine; Fig. 17 is a detail elevation of one of the top folders and its carrier; Fig. 18 is a section on a line 18—18 of Fig. 17; and Fig. 19 is a diagrammatic elevation.

For the sake of simplicity, we shall use the term "box" in this description to designate either the body of a box or the cover thereof, since both of these parts are similar and are wrapped with a strip of paper or the like, in the same manner. A brief explanation of the sequence of operations performed by the particular machine illustrated herein is as follows: The box is first contained in a carrier or holder, from which it is expelled by the action of a plunger or core entering the box; while the box is on the plunger, the latter is rotated to apply to the box, the end of which is held between said plunger and a yielding box-retainer, a strip of paper or other flexible material the edges of which project beyond the side walls of the box both at the closed end or so-called bottom, and at the open end or so-called top. The strip having thus been wrapped around the box, the plunger, with the box thereon, is brought from the position in which it registers with the wrapping device, to another position in which it brings the box into operative relation to folders which bring one projecting edge of the wrapped strip against the bottom of the box. The retainer, which until that time has remained in engagement with the box bottom, is then moved out of the way, clearing the path of the box which is brought forward by a further advance of the plunger, against and into a die which at that time is in line with the path of the plunger. The latter is then retracted from the box, which remains held by the die, and this die, with the box, is then moved transversely, to a different position, and during

this transverse motion the projecting edge of the strip at the open end of the box is folded inwardly into a plane perpendicular to the sides of the box. Thereupon another plunger, operating in line with the second position of the die, advances into the box to fold the top edges of the paper strip against the inner surfaces of the box-sides, that is to say, into the box. After this operation, 10 outside pressers press the paper strip firmly against the outside of the box, and also cause the inwardly-folded top edges of such strip to be pressed tightly between the second plunger (the pressure-plunger) and the side 15 walls of the box. Then an ejector engaging the box bottom on the outside, moves the box out of the die which has been holding it, and the pressure-plunger is retracted, the box coming into engagement with stationary 20 stops which cause it to be stripped off the pressure-plunger as the latter is retracted.

The particular container or holder shown in Figs. 1, 2, 4, and 10 comprises two spaced members or carriers 20 located at the same 25 level and carrying the box-guiding and box-holding parts. The box A (which may be either a box body or a cover), when received within said container or holder, has one of its four side walls 21, which at that time is 30 lowermost, resting on two projections 22 extending toward each other from the lower ends of two vertical bars 23, secured to a pair of substantially vertical side walls 24 adapted to act as guides for the two side 35 walls 21 which at that time are vertical. The bars 23 are secured to the guides 24 in any suitable manner, as by screws 25, preferably in such a way as to allow the bars 23 with their box-supporting projections 22 40 to be adjusted up and down, for which purpose said bars may be slotted vertically, as indicated at 26, for the passage of said screws, the latter being drawn up tight after the desired adjustment has been made. The 45 guides 24, which preferably diverge at their upper ends as shown, to facilitate the entrance of the box, are secured rigidly to brackets 27, which are fastened to the carriers 20, preferably in such a manner as to 50 allow these brackets to be adjusted horizontally toward and from each other, for which purpose these brackets may be slotted horizontally in a manner corresponding to that explained with reference to the bars 23. To 55 the guides 24 are secured bearings 28 for vertical shafts 29, and on these shafts are mounted horizontally-rocking arms 30, 31, the portions 30 being formed with eyes as shown best in Fig. 10, and the portions 31 60 being connected at their free ends by vertical abutment bars 32. To the guides 24 are also secured rigidly horizontal pins 33 extending loosely through openings of the arm portions 31 and carrying collars or washers 34 65 engaged by the outer ends of coiled springs

35, the inner ends of which press the arms 30, 31 toward each other and into engagement with the guides 24, the bars 32 having seats or engaging surfaces 32' normally in the path of the closed end or bottom 70 36 of the box A.

We have also indicated the following mechanism for delivering to the container or holder, partly-finished boxes, that is to say, 75 boxes each comprising a flat end wall or bottom and four side walls perpendicular to said bottom, said side walls preferably having overlapping ends pasted together: A chute 37 of open-work character, and preferably adjustable to different sizes of boxes, 80 is arranged to feed or guide the said boxes from a magazine (not shown) or otherwise to the box-holder when the latter is in registry with the lower or delivery end of said chute, as in Fig. 1; the open side or end of 85 each box will face toward the left in Fig. 1, and the closed end or bottom toward the right. The guides 24 are adjusted to such a distance from each other that at the time a box is allowed to slide down from the chute 37 to the holder, such lowermost box will by 90 its own weight drop into contact with the supporting projections 22, as in Figs. 1 and 4, the weight of the other boxes assisting in pressing such box down. The holder is 95 open not only at the top, for the introduction of a box from the chute 37, but also on the two ends which correspond to the open end and to the closed end of the box respectively; that is to say, the holder is also open at the 100 left and at the right in Figs. 1 and 2.

While we have shown a wrapping machine having a holder to which partly-finished boxes (produced elsewhere) are supplied 105 from a chute, we desire it to be understood that this is immaterial so far as certain broad features of our present invention are concerned, and instead of being fed through a chute as set forth, in a partly-finished condition, the boxes might be produced on the wrapping machine itself, for instance in the manner disclosed in the pending application for Letters Patent of the United States, Serial Number 417,014 filed on October 14, 1920 by one of us (Martin Feybusch) and Sigurd Severson, in which case the "former" 110 42 of said co-pending application would take the place of the box-holder or container of the present application (indeed, said "former" might be termed a box-holder or container), while the core 41 of said earlier application would correspond to the core or plunger 38 of the present case.

This core or plunger 38 is of proper rectangular shape to enter the box A fitted 115 within the holder or container, and preferably the front edges of the core are rounded as shown so that it may enter the box readily and cause such box to become properly centered on the core. In order to fit boxes of 120

different sizes, different cores are employed, the core 38 being secured exchangeably to a centrally-located horizontal rod or shaft 39. The core 38 is not only adapted to be 5 rotated for the purpose of the wrapping operation to be referred to presently, but is also capable of horizontal movement, in the direction of the axis of the shaft 39, this longitudinal movement taking place 10 in stages as explained below. We have not illustrated herein any particular mechanism for effecting this longitudinal motion and the rotation of the core 38, since this mechanism may be of the same character as shown 15 in the earlier application mentioned above, or any other mechanism that will accomplish the desired result may be employed.

At the time the holder is in position to receive a box, as in Fig. 1, the core 38 is re- 20 tracted fully, being in the extreme position to the left, as shown in Fig. 1, and also helps to guide the open end of the descending box. The box-holder, while non-rotary, is movable lengthwise of the axis of the shaft 39; 25 for this purpose, the carriers 20 are secured to two horizontal rods 40 parallel to the shaft 39 and arranged on opposite sides thereof. A longitudinal sliding movement may be imparted to the said rods and to 30 the box-holder in the proper direction and at the proper time in any suitable manner, for instance by means of the character set forth in our aforesaid earlier application with reference to the movement of the 35 "former" 42. The shaft 39 and the rods 40 are shown supported in a stationary member 41 forming part of the frame of the machine.

While the parts are in the position indicated in Fig. 1, the box A immediately above the one in the holder is lifted out of contact with said lowermost box, in any suitable manner. As an instance of mechanism 40 for retaining temporarily in the chute 37, the boxes contained therein, and for effecting the release of the box in the holder, from the weight of the other boxes, we have shown a rocking arm or finger 42, fulcrumed on a stationary part at 43, which finger in one 45 position, Fig. 1, clears the path of the boxes A so that they may slide down freely in the chute 37. At the proper moment through suitable mechanism (not shown) controlled automatically from the main shaft or some 50 other moving part of the machine, this finger is rocked to the position shown in Fig. 2, in which it enters the open end of the lowermost box A contained in said chute, through a suitable opening in the left-hand 55 wall of the chute, and by bearing against that side wall 21 of the said box which is at the top of the box, lifts said box as shown, thereby supporting this box and all those above it, and freeing the lowermost box A, 60 which is in the holder. We may add that

the finger 42 is, for the greater part of the time, in the position shown in Fig. 2, the position Fig. 1 being taken only at the time a box is to be fed from the chute 37 to the holder. 70

The core 38, which at the time stands in a position corresponding to that of the holder and of the box therein, that is, with the side edges vertical and horizontal respectively, is then moved from the extreme position indicated in Fig. 1, toward the right, to an intermediate position such as indicated by dotted lines in Figs. 1 and 2, this movement of the core being purely longitudinal, without rotation. At the same time, the holder 75 is retracted from the position shown in Fig. 1, to that shown in Fig. 2, so that the holder, which originally was in advance (to the right) of the core 38, will now be at the rear (to the left) thereof. This movement of the 80 holder and of the core past each other in opposite directions, causes the core to enter the box carried by the holder, and said box to be stripped off the holder and transferred to the core. In order to insure the core's 85 entering the box fully, so as to come in contact with the closed end or bottom 36 of the box, we have provided on the holder, yielding stops, such as the bars 32, adapted to engage the box bottom 36 on the outside (on 90 the right in Figs. 1 and 10). These will oppose a sufficient resistance to a movement of the box relatively to the holder, to the right, to compel the box and holder to move in unison toward the left, notwithstanding 95 any frictional engagement of the core 38 with the inner surfaces of the side walls 21, until the end of the core comes in contact with the inner surface of the closed end or bottom 36; from that moment on, the box 100 will move in unison with the core, and not with the holder, the stops or bars 32 yielding to let the box pass between them. 105

While the core 38 is in the intermediate position referred to above, it is in operative 110 relation to mechanism for wrapping a strip 44 of paper or other flexible material around the box, the core being rotated for this purpose in any approved manner, the principle of this operation being well-known in the 115 art; a suitable wrapping mechanism is set forth in our earlier application herein referred to, and in the present case we have deemed it sufficient to indicate the wrapping strip 44 and a roller 45 which forms part of 120 the wrapping mechanism, said roller pressing the gummed strip against the outside of the box walls 21 as the core rotates. (Figs. 1, 2 and 11.)

A novel feature of our present invention 125 which is of importance in conjunction with the wrapping step and subsequent stages of the operation, consists in a box-retainer 46 adapted to engage the box bottom 36 on the outside, both during the wrapping and dur- 130

ing certain steps subsequent thereto, as will be set forth below. This retainer preferably is made as a roller mounted to turn about an upright axis at the lower end of an arm 47 which at its upper end has a pivotal connection 48 about a horizontal axis transverse to the direction in which the box-holder and the core 38 move; by this connection 48 the arm 47 is hung from a lever 49, fulcrumed on the frame of the machine at 50, about a horizontal axis parallel to the pivot 48. The opposite, left-hand end of the lever 49 is connected with mechanism for rocking said lever and operating the retainer 46 at the proper times; we have shown an upright rod 51 the upper end of which is pivoted to the lever 49 at 52 about an axis parallel to 48 and 50, while the lower end of the rod 51 is secured to a guide member 53 having a portion 54 straddling a shaft 55 (which may be the main shaft of the machine), and provided with a roller 56 working in a cam groove 57 on a disk 58 carried by said shaft to rotate therewith. A spring 59 tends to pull the arm 47 toward the lever 49, and to keep said arm, in its initial position illustrated by Fig. 1, in contact with a guide (preferably a roller) 60 mounted on a stationary portion of the machine. As the box and core approach the wrapping position indicated by dotted lines in Figs. 1 and 2, and slightly before this position is reached, the retainer 46 will come into engagement with the box bottom 36 on the outside thereof, and the pressure of the spring 59 will thus be exerted through the said retainer 46 to keep the box A in proper position against the core 38. If no retainer is employed, there is danger that the box, owing to the rapid motion of the parts and the momentum acquired by the box, or owing to other causes, will become loose on the core or fly ahead of its proper position, as it were. With the use of our retainer, the box is held with certainty in proper position for wrapping and for certain subsequent operations.

In the wrapping position, therefore, the arm 47 is out of contact with the roller 60, although not quite so far away therefrom as indicated in Fig. 2 (full lines) which illustrates a subsequent position. The strip 44, in the machine shown, is wrapped around the box A in such a manner that the edges of the strip will project from the box both at the closed end or bottom 36, and at the open end, see Figs. 2 and 11, which show the strip 44 as of greater width than the sides 21 of the box, and as projecting therefrom both at left and right.

The strip 44 having been wrapped around the box, its projecting edges are to be folded against the box. First, the edges projecting adjacent to the closed end or bottom 36 are folded, that is to say, the so-called bot-

tom edges. For this purpose, the core 38 with the box thereon, is advanced from the wrapping position (dotted lines in Figs. 1 and 2), to the bottom-edge folding position, indicated by full lines in Fig. 2. The spring 59 will yield to allow the arm 47 to move slightly more to the right, and the retainer 46 will therefore press with slightly increased force against the box bottom 36, holding the latter quite firmly against the core 38 in this position. This movement of the core brings the outer (right-hand) surface of the bottom 36 close to the path of bottom-edge folders 62, 63 mounted to slide horizontally and vertically respectively in a suitable stationary support 64 having an opening 65 wide enough to allow the box A and the core 38 to pass therethrough. It will be understood, particularly with reference to Fig. 3, that at the end of the wrapping operation the core and the box thereon are in a position with the sides 21 vertical and horizontal respectively, so as to co-operate properly with the inner edges of the bottom-edge folders 62 and 63 respectively. The arrangement and the operation of these folders may be varied; a suitable mechanism for operating such folders is disclosed in the earlier application mentioned above, but we do not desire to restrict ourselves to sliding folders, or to any specific mechanism for operating the bottom-edge folders. It will be understood that the function of these folders is to bend or fold the bottom edges of the strip 44 until they all lie in the same plane, flat against the outer surface of the closed end or bottom 36.

When this operation has been performed, the box-retainer 46 is moved out of contact with the bottom 36, and out of the path of the box A, to the inactive position indicated by dotted lines in Fig. 2; this movement of the retainer 46 and of the arm 47 is effected by the action of the cam groove 57 on the roller 56, said arm coming in contact with the roller 60, and sliding over it.

The box-retainer having thus been swung out of the way, the core 38 with the box A thereon, and with the wrapped strip 44 folded against the outside of the bottom 36, at the right-hand edge of said strip, is moved still further toward the right, to the end of its right-hand throw or stroke, thereby carrying the box A into a die which at that time is in position to receive the box. The resulting position is substantially as shown in Fig. 8, except that the latter illustrates a slightly later stage at which the core 38 is no longer within the box. The core 38 at the end of its stroke to the right (forward stroke) brings the bottom 36, or rather the folded edge of the strip 44 which lies against said bottom, into contact with a back-plate 66 which forms part of the said die. This back-plate has an opening 67 for

the passage of an ejector described herein-after, and is preferably removable and exchangeable, different back-plates being used for different-sized boxes. We have indicated 5 a back-plate adapted to slide in dovetail fashion, in vertical guideways 68 of two vertical side strips 69 which are secured, as by screws 70, to a slide 71 movable horizontally, in a direction transverse to the shaft 10 39 and to the rods 40, in guideways 72 of a stationary frame portion 73 (Figs. 8 and 13). Any suitable mechanism is provided for reciprocating this slide 71 along the guideways 72, for instance, as indicated at 15 74 in Fig. 8, said slide may be connected pivotally with a pitman or actuating rod 75 receiving its motion from the main shaft in any suitable manner. The strips 69 carry hubs 76 integral or rigid therewith, and 20 through these hubs extend rods 77, perpendicular to the plane of the slide 71, and parallel to the shaft 30 and rods 40. The rods 77 may be adjusted in the hubs 76 lengthwise, and secured in position after adjustment, by means of set screws 78. The rods 77 carry vertical strips 79 (Figs. 8 and 14) on which are mounted carriers 80, 81 respectively. The carriers 80, 81 are provided with horizontal slots 82, 83 respectively 25 (Fig. 6), which are parallel to the direction in which the slide 71 moves, and through these slots extend screws 84, 85 respectively, screwing into the said strips 79. Normally, the screws are drawn tight so 30 that the carriers 80, 81 are rigid with the slide 71, but upon loosening said screws, the carriers 80, 81 may be adjusted individually toward or from each other, to adjust relatively to each other, vertical strips 86, 87 35 respectively which are connected with said carriers and which engage the two vertical side walls 21 of the box A. The strip 86 is secured rigidly to its carrier 80, but the other strip, 87, is movable relatively to its 40 carrier 81, in the same direction in which the carriers 80, 81 are adjustable relatively to the strips 79. For this purpose, the strip 87 is secured to a plate 88, from which extend horizontal rods 89, parallel to the path 45 of the slide 71, and forming guides for a sliding cross-head 90, the rods 89 being suitably guided for sliding movement in the carrier 81, in a direction parallel to the path of the slide 71. The cross-head 90 is 50 adapted to be pressed against collars 91, secured to the outer ends of the rods 89, by springs 92 coiled around said rods and bearing with one end against the cross-head, and with the other against collars 93 rigid 55 on said rods. The cross-head 90 is further urged outwardly relatively to the carrier 81, by springs 94 the respective ends of which engage the said carrier and said cross-head, see Fig. 6. In the central portion 60 of the cross-head is secured an abutment 95, preferably adjustable lengthwise of the path of the slide 71, for which purpose said abutment may consist of a screw screwing into the cross-head 90, see Figs. 6 and 8, and extending loosely through the 70 carrier 81, said screw, after adjustment, being locked against turning, by means of a set screw 95'. In a bracket 96, rigid with the frame portion 73, is journaled at 97 a rocking elbow lever 98, one arm of which is adapted to engage the abutment 95, while the other arm is adapted to be engaged by operating mechanism described below. 75 The vertical strips 86, 87 have their lower ends close to a horizontal strip 99 (Figs. 6 and 8) of similar character, adapted to engage the lower horizontal side wall 21 of the box A, and this strip has preferably attached thereto an additional support 100 extending toward the back plate 66. The 80 strip 99, with said support 100, is adjustable up and down along the vertical strips 79. A major vertical adjustment may be effected by transferring up or down, the screws 101 which normally hold said strip 99 rigidly 85 on the strips 79; for this purpose, we have shown the strips 79 as having a series of vertically-superposed screw-threaded openings 102 to receive said screws 101 (Figs. 6, 15 and 16). A minor or more accurate up 90 and down adjustment of the strip 99 may be effected by loosening the screws 101, and then sliding said strip up or down to the desired extent, the ends of the strip being provided with vertical slots 103 through 95 which said screws extend, the screws being tightened after the adjustment. 100

Adjacent to the upper ends of the strips 86, 87, but normally out of contact therewith, as indicated by the space 104 (Fig. 6), is an upper horizontal strip 105, similar in shape and length to the lower strip 99, the latter, however, being in contact with the lower ends of the strips 86, 87, and normally rigid with the strips 79; on the other hand, the upper strip 105 is movable vertically toward the upper ends of the strips 86, 87, Fig. 6 showing the raised position 105 of the strip 105. To effect a downward movement of the strip 105, we have shown vertical rods 106 connected with said strip rigidly, said rods being fitted to slide in suitable bosses forming part of a carrier 107 which is normally rigid with the strips 79, but may be adjusted relatively thereto 110 by a construction similar to that set forth in connection with the lower strip 99. That is to say, the strips 79 have a second series of vertically superposed threaded openings 102', adapted to receive the screws 108 extending through vertical slots 109 of said carrier 107. The rods 106 also extend through a cross-head 110 (similar to the cross-head 90), and springs 111 interposed 115 between said cross-head and the bosses on 120

125

130

the carrier 107 tend to keep said cross-head in its outer position, against collars 112 at the outer ends of the rods 106, thereby tending to keep the upper strip 105 in the outer or upper position shown in Fig. 6, that is to say, against the carrier 107. The rods 106 extend through the cross-head 110 loosely, so that the latter may have a limited sliding movement on said rods, between the 10 collars 112 and inner collars 113, cushioning springs 114 being coiled around the rods 106 between the said collars 113 and the cross-head 110. Through the central portion of the cross-head extends an abutment, 15 here shown as a screw 115 having threaded engagement with the cross-head, the outer or upper end of said abutment being adapted for engagement with operating mechanism as will be described below, and after 20 being adjusted up or down relatively to the cross-head to the desired position, the abutment 115 may be locked by a set screw 116. It will be noted that the mechanism connected with the upper strip 105 is similar 25 to that described in connection with the movable vertical strip 87. We may add that the carrier 81 of said movable strip 87 is preferably also adapted for a major adjustment in addition to the minor adjustment set forth above, and for the purpose 30 of this major adjustment the strip 79 on which said carrier is mounted has a plurality of openings 79' (Fig. 16) for each of the screws 85, the openings for the same 35 screw being located at the same level, so that the screws 85 may be shifted to different positions, right or left, thereby providing a greater range of adjustment than is obtained by the slots 83 alone. A similar 40 arrangement may be provided for the screws 84 securing the carrier 80.

In a position adjacent to the strip 86 when the latter by the transverse movement of the slide 71, has been carried to the position shown in Fig. 6, is located a vertical shaft 117, mounted to rock in arms 118, 119. The lower arm 119 is carried adjustably by a rod 120 secured to a stationary part of the machine, for instance the support 64 of the 50 bottom-edge folders 62, 63 (see Fig. 2); this stationary rod 120 extends transversely to the path of the slide 71, and after adjustment along said rod, the arm 119 is locked by a set screw 121 or in any other suitable 55 manner. The upper arm 118 is made integral or rigid with a bar 122 parallel to the rod 120 and slotted lengthwise for the passage of an adjusting and locking screw 123 by which said bar is secured adjustably to 60 a bracket 124 secured to the frame portion 73. On the rock shaft 117 is secured rigidly an arm 126 carrying a roller 127 adapted to engage a cam 128 which is secured to the lower ends of the strips 79 (Figs. 6 and 65 7). A spring 129 tends to rock the shaft 117

in such a manner as to keep the roller 127 in contact with the cam 128. The shaft 117 carries rigidly a yielding folder blade or strip 125, extending vertically not quite to the level of the upper and the lower ends of the strips 86, 87 (Figs. 6, 8 and 9).

The arms 118, 119 are connected by a bar 130 fastened thereto by screws 131, and along this vertical bar are adjustable two brackets or carriers 132 (Figs. 6, 17 and 18), locked 75 in position by screws 133 extending through slots 132' of the brackets, this arrangement permitting a minor adjustment of the brackets up and down. A major adjustment may be obtained by engaging the screws 133 80 with different openings 130' of the bar 130. To the carriers 132 are pivoted about vertical axes 134, folders 135 urged by springs 136 against positioning set screws 132'' and adapted to engage and fold the horizontal 85 portions of that part of the strip 44 which projects at the open end of the box (the so-called top); the folder blade 125 is adapted to engage one of the vertical portions of the projecting strip 44, at the open end of the 90 box.

For folding the other vertical portion of the strip 44, at the open end of the box, we have provided the following mechanism (Fig. 6): On the carrier 80 are mounted 95 rigidly two horizontal guides 137, parallel to the path of the slide 71, and along said guides is movable a slide 138 carrying a vertical folder 139 the upper and lower end portions of which project far enough to overlap the folders 135, or at least the lower portions of said folders; the upper and lower ends of the folder 139 may, for instance, be at substantially the same levels 100 as the opposing or operative surfaces of the strips 105 and 99 respectively. To operate the folder 139, we have provided a bell crank lever 140, fulcrumed on the left-hand strip 79 at 141, and having a pin-and-slot connection 142 with the slide 138 (Figs. 6 and 8). 110 The lever 140 carries a roller 143 traveling in a suitable groove of a cam 144 which extends parallel to the path of the slide 71. The cam 144 is normally stationary, but may be adjusted toward or from the frame portion 115 73. For this purpose, the cam has bosses through which extend parallel rods 145 (Figs. 6 and 7), set screws 146 serving to lock the cam to said rods after adjustment. The rods 145 have their inner ends fitted into 120 bosses formed on a bracket or carrier 147 secured to the frame portion 73, and pins 148 are shown as means for securing the rods 145 to said carrier.

Fig. 6 shows the following mechanism for 125 operating the movable strips 87 and 105: On the frame of the machine is journaled a shaft 149 to which a rocking motion is imparted at the proper times by a cam or other suitable mechanism of any approved char- 130

acter (this mechanism is not shown). This rock shaft has an arm 150 connected pivotally at 151 with a rod or link 152 extending upwardly and carrying a tappet 153, which 5 may be adjustable vertically along said link. This tappet engages the elbow lever 98, and is adapted to rock the same to engage the abutment 95 and move the vertical strip 87. The upper end of the link 152 is connected 10 pivotally at 152' with one end of a lever 154, fulcrumed at 155 on a stationary part of the machine and provided, at its other end, with an operating lug or knob 156 adapted to register with the upper end of the abutment 15 115 when the latter is in the position shown in Fig. 6. The term "die" is herein applied to the box-receiving parts carried by the slide 73, that is to say, particularly, to the back-plate 66 and the strips 86, 87, 99 and 20 105. The back-plate is supported in any suitable manner, for instance by means of a lug 66' (Fig. 13) resting on the upper end of one of the strips 69, and at 66'' we have indicated holes through which the attendant 25 may insert his fingers so as to better grasp the back-plate when inserting or removing it.

The box A having been brought into the die while the latter is in the position indicated in Fig. 8, the core 38, which at the time of the bringing the box into the die is in contact with the inner face of the box bottom 36, in the same relative position as indicated in Fig. 11, is withdrawn therefrom 30 toward the left, to the original position of the core as indicated by full lines in Fig. 1. The core 38 therefore is now clear of the path of the die, and the latter is free to move with the slide 71, from the position shown 35 in Fig. 8 and indicated at *a* in Fig. 6 at the left, to the position shown in full lines, at the right of Fig. 6, and Fig. 9 illustrates an intermediate position which occurs shortly 40 after the beginning of this movement, it being understood, however, that the movement of the die from the position Fig. 8 to the position Fig. 6 at the right, is continuous. In the initial or normal position, the folders 125 and 139 are in their inactive or retracted 45 position; Fig. 8 shows the inactive position of the folder 125, see also Fig. 7, and the folder 139 is in its inactive position when the slide 138 is at the left-hand end of its stroke in the guides 137, that is when the 50 roller 143 is at one of the depressed end portions of the cam 144; Fig. 6 shows the folder 139 in such inactive position, and it will be understood that with the die in the initial position, Fig. 8, the roller 143 will be at the 55 left-hand end of the cam 144, but the lever 140 and the parts connected therewith (slide 138 and folder 139) will be in the same position relatively to the die as in Fig. 6. As 60 the die with the parts carried thereby moves to the right, from the position shown in Fig. 55 65 8 to that illustrated by Fig. 6, the cam 128, moving with the die, will by its engagement with the roller 127, swing the arm 126, the rock shaft 117, and the folder 125, from the inactive position Figs. 7 and 8, to the active 70 75 position shown in Fig. 9. The folder 125 thus comes close to the path of the open end of the box A, and folds inwardly, the portion of the strip 44 which extends vertically along the right-hand side 21. At substantially the same time, the action of the stationary cam 144 on the roller 143, as said roller rides up the incline shown at the left in Fig. 6, shifts the folder 139 from the inactive position shown in Fig. 8 (in which it 80 does not project to the right of the side strip 86), to the active position, Fig. 9, in which such folder projects to the right of said strip 86, and thus the left-hand vertical portion of the strip 44 is folded inwardly. Immediately thereafter, the upper and lower folders 135 come into engagement with the upper and lower portions of the strip 44, lying along the horizontal sides 21 of the box, and likewise fold these strip portions 90 inward. The result of this folding operation is to bring that portion of the wrapping strip 44 which projects at the open end of the box, from a position perpendicular to the plane of the bottom 36, to a position parallel 95 with said plane. It will be noted that the folders 125 and 135 do not share the movement of the die, that is to say, the box A carried by said die moves past these folders; the folder 139, however, moves with the die. 100 The yielding mounting of the folders 135 at 134 is simply for the purpose of adjusting them accurately by the aid of the set screws 132'', and said folders 135 are set in such a manner that the folder 139 will not come in 105 contact with them, see Fig. 12. Before the folder 139 reaches the folder 125, the latter is swung out of the way, to the inactive position, as the roller 127 reaches the right-hand incline of the cam 128, see Fig. 7. All interference between the action of the relatively stationary folders 125 and 135 and of the relatively movable folder 139 is thus avoided. 110 This operation having been completed, and the die remaining in the same position, a 115 pressure-plunger 157 is advanced into the box to fold the edges of the wrapping strip 44 which have just been bent into the same plane by the action of the folders 125, 135, and 139, into the box and against the inner 120 surfaces of the four box sides 21. This plunger 157 moves in a direction parallel to the path of the core 38, and may be constructed and operated in any suitable manner, for instance as set forth in our earlier 125 application mentioned above. While this plunger is within the box, as indicated in Fig. 19, the rock shaft 149 is operated to bring the two strips 87 and 105 toward the strips 86 and 99 respectively, it being under- 130

stood that at that time the abutments 95 and 115 are in registry with the respective operating members 98 and 156, as shown in Fig. 6. The strips 87, 105 being moved as set forth, will press the box firmly against the plunger 157 and against the relatively stationary opposing strips 86 and 99, the plunger being mounted with sufficient looseness so that the pressure of said strips 87, 105 will be transmitted by the plunger 157 to the box sides 21 which lie adjacent to the strips 86 and 99, respectively. The movable strips 87, 105 therefore constitute pressers to insure the proper adherence of the wrapping strip 44 at the open end of the box, both on the inner and on the outer surface of said box.

Preferably, after this pressure has been exerted and when the pressers 87, 105 have been moved again to the releasing position shown in Fig. 6, the plunger 157 is given a slight additional movement toward the box bottom 36, for instance to the position indicated by the dotted line in Fig. 19, so as to release the plunger from the wrapping strip 44 in case any glue should come between the plunger and said strip.

The subsequent operations may consist in expelling the box A from the die, as by means of an ejector 158, the operating mechanism of which may be of the same type as disclosed in the aforesaid application. Plunger and ejector may thereupon be moved in unison by any suitable means, to carry the box against stationary stops 159, whereupon the plunger 157 will continue to move alone, so that the box A, being arrested by the stops 159, will be stripped off the plunger 157 and dropped, for instance into a chute 160 leading to a suitable support, such as a table or a conveyor (not shown), the box thus discharged being taken away manually or mechanically.

Figs. 12 and 19 show the depth of the plunger 157 as slightly greater than the width of the strip portion folded inside the box; the edge folded against the bottom 36 is in its entire width, in contact with the back plate 66.

50 We claim as our invention:

1. In a machine of the class described, a box holder movable lengthwise of its axis, means for wrapping a flexible strip around a box carried by said holder, and a retainer located in the path of the box carried by said holder and arranged to engage the bottom of said box when the latter is in operative relation to the wrapping means.

2. In a machine of the class described, means for wrapping a flexible strip around a box and subsequently folding the projecting edges of the said strip at the closed end of the box against the box bottom, a die arranged to receive the box after the strip has been wrapped around the box and folded

against its bottom, a retainer arranged to engage said box bottom during the wrapping operation and while the edges of the strip are being folded against such bottom, and mechanism for moving said retainer away from the box bottom before the latter comes into the die.

3. In a machine of the class described, a movable box support, means for wrapping a flexible strip around the box carried by said support and for subsequently folding that edge of said strip which projects at the closed end of the box, against the box bottom, a die arranged to receive the box after the said strip has been wrapped around it and folded against its bottom, a retainer arranged in the path of the box between said support and said die, to engage the bottom of the box, and means for removing said retainer from the path of the box bottom after the said edges have been folded.

4. In a machine of the class described, a movable box support, wrapping and folding mechanism with which said support and the box therein are brought into operative relation successively by the movement of the support, a die into operative relation with which the box is brought by a further movement of said support, and a box-retainer arranged in the path of the box bottom and movable aside from said path before the box reaches the die.

5. In a machine of the class described, a movable box support, means for wrapping a flexible strip around a box carried by said support, a die arranged to receive the box after such strip has been wrapped thereon, a box-retainer located between the support and the die and arranged to engage the bottom of the box, and means for removing said retainer from the path of the box bottom.

6. In a machine of the class described, a movable box holder, a core arranged to fit into the box carried by said holder, and movable in the same direction as the holder, means for wrapping a strip of flexible material around the box while supported by said core, a die arranged to receive the box after such strip has been wrapped thereon, a box-retainer located between the core and the die and arranged to engage the bottom of the box, and means for removing said retainer from the path of the box bottom.

7. In a machine of the class described, a core arranged to fit into a box and to support the same, means for wrapping a flexible strip around said box while supported by said core, a die arranged to receive the box after such strip has been wrapped thereon, means for effecting relative movement of the core and the die to transfer the box from said core to said die, a box-retainer located between the core and the die and arranged to engage the box, and means for removing said retainer from contact with the box.

8. In a machine of the class described, a chute for feeding boxes, a box-holder movable into and out of registry with said chute, a core arranged to fit into the box carried by the holder, said core being movable in the same direction as the holder and forming a guide for the box as it comes down from the chute into said holder, and means for moving said holder and said core. 5
9. In a machine of the class described, a chute for feeding boxes, a box-holder arranged to receive boxes from said chute, a core arranged to fit into the box carried by said holder, said core forming a guide for the box as it comes down from the chute into the holder, and means for effecting relative movement of said holder and said core to transfer the box from the holder to the core. 10
10. In a machine of the class described, a holder arranged to receive a box, a core arranged to enter said box, and means for effecting relative motion of the said core and said holder to transfer the box from one of them to the other, said holder being provided with yielding stops arranged to engage the box at the end opposite to that from which the core enters. 15
11. In a machine of the class described, a holder arranged to receive a box and having upright side walls and projections located adjacent to the lower ends of said walls and extending toward each other to form a support on which the box rests. 20
12. In a machine of the class described, a box-holder having upright side walls and vertically-adjustable projections extending toward each other near the lower ends of said walls, to act as supports for the box. 25
13. In a machine of the class described, a box-holder having upright side walls adjustable toward and from each other, and projections located adjacent to the lower ends of said walls and extending toward each other to form a support on which the box rests. 30
14. In a machine of the class described, a box-holder having upright side walls adjustable toward and from each other, and projections carried by said walls at their lower portions and adapted to act as supports for said box, said projections being adjustable toward and from each other in unison with said walls, and being furthermore adjustable up and down relatively to the respective walls. 35
15. In a machine of the class described, a box-holder having upright side walls, arms pivoted adjacent to said walls about upright axes, abutments secured to said arms and projecting inwardly beyond said side walls to engage the box under normal conditions, and springs pressing said arms toward such normal position and enabling them to swing aside yieldingly to allow the box to become disengaged from the holder. 40
16. In a machine of the class described, a box-holding die, a folder mounted on said die movably and arranged to fold one edge portion of a flexible strip wrapped around a box held in said die, another folder mounted to swing about a stationary axis and adapted to fold an edge portion of said strip which is parallel to the first-named edge portion, and means for swinging said second-named folder about its stationary axis to clear the path of the first-named folder as the latter moves with the die. 45
17. In a machine of the class described, a box-holding die movable parallel to the bottom of a box held in such die, a folder mounted on said die movably and arranged to fold one edge portion of a flexible strip wrapped around such box and projecting from the open end thereof, another folder mounted movably on a stationary support, independently of said die, adjacent to a portion of the path of said die, and adapted to fold an edge portion of said strip which is parallel to the first-named edge portion, and means for moving said second-named folder out of the path of the first-named folder as the latter moves with the said die. 50
18. In a machine of the class described, a box-holding die arranged to reciprocate, a folder mounted on said die movably and arranged to fold one edge portion of a flexible strip wrapped around a box held in said die, another movable folder mounted independently of said die so that the reciprocating movement of the die will carry the box past said second-named folder, the latter being adapted to engage and fold an edge portion of said strip parallel to the first-named edge portion, means for moving the first-named folder relatively to the die during the movement of the latter, and means for moving the second-named folder out of the path of the first-named folder as the latter moves with said die. 55
19. In a machine of the class described, a box-holding die mounted to slide, folders mounted on said die to engage a wrapping strip on a box held in said die, at those portions of said strip which are parallel to the path of the die, and means for adjusting said folders relatively to the path of the die. 60
20. In a machine of the class described, a movable box-holding die, spring-pressed folders mounted on said die movably and adapted to engage a wrapping strip on a box held in said die, at those portions of said strip which are parallel to the path of the die, and adjustable stops determining the normal position of said folders. 65
21. In a machine of the class described, a die arranged to support a box, a plunger for folding a wrapping strip into said box while the latter is carried by such die, an ejector working in line with the plunger to separate the box from the die, and a stop for engaging 70
- 75

ing the box and stripping it off the plunger after the box has been separated from the die.

22. In a machine of the class described, a die arranged to support a box, folding means cooperating with said die to bend the edges of a strip wrapped around the box and projecting at the open end thereof, a plunger for turning the folded edges of said strip into the box while the latter is carried by the die, an ejector working in line with the plunger to separate the box from the die, and a stop for engaging the box as it moves with the plunger after being separated from the die, and for stripping the box off said plunger.

23. In a machine of the class described, a box-holding die having movable pressers to engage the box, movable members for actuating said pressers, and elastic members interposed between said actuating members and the pressers and yieldingly transmitting the motion of said actuating members to said pressers.

24. In a machine of the class described, a box-holding die having mounted thereon movably a presser adapted to engage the box, a coiled spring one end of which is in operative engagement with said presser, and a movable actuating member engaging the other end of said spring.

25. In a machine of the class described, a box-holding die having mounted thereon movably a presser adapted to engage a side wall of the box, a movable actuating member, and a yielding motion-transmitting member forming an operative connection between said actuating member and said presser.

26. In a machine of the class described, a box-holding die comprising supports provided with series of openings, walls adapted to engage sides of the box, and provided with slots the direction of which corresponds to the direction of said series of openings, and screws for securing said walls to said supports, said screws being adapted to be inserted in the various openings of said series, and also extending through said slots of the walls.

27. In a machine of the class described, a box-holding die comprising supports, attaching devices displaceable to different positions on said supports, and a wall adapted to engage a side of the box and secured to said supports by said attaching devices, said wall being also adjustable relatively to such attaching devices.

28. In a machine of the class described, a box-holding die comprising supports, attaching devices displaceable to different positions on said supports, and a wall adapted to engage a side of the box and secured to said supports by said attaching devices, said wall having slots extending in the direction

in which said attaching devices are displaceable on said supports, said attaching devices extending through said slots.

29. In a machine of the class described, a box-holding die comprising a die body, attaching means displaceable to different positions on said body, and a wall adapted to engage a side of the box and secured to said body by said attaching means, said wall being slotted in the direction in which said attaching means is displaceable on said body, and said attaching means extending through the slotted portion of said wall.

30. In a machine of the class described, a box-holding die comprising a die body, attaching means displaceable to different positions on said body, and a wall adapted to engage a side of the box and secured to said body by said attaching means, said wall being also adjustable relatively to said attaching means, in the same direction in which such means is displaceable on said body.

31. In a machine of the class described, a box-holding die comprising a die body, a presser mounted on said body movably and adapted to engage a side of the box, an actuating member movable on said body in the same direction as said presser, a spring interposed between said member and said presser, an abutment adjustable relatively to said actuating member lengthwise of the path of said member, and operating means adapted to engage said abutment.

32. In a machine of the class described, a box-holding die having a body, a presser mounted on said body movably and adapted to engage a side of the box, an actuating member movable on said body in the same direction as said presser and connected with such presser, an abutment carried by said actuating member and adjustable relatively thereto lengthwise of the path of said member, and operating means adapted to engage said abutment.

33. In a machine of the class described, a box-holding die having a body, a presser mounted on said body movably and adapted to engage a side of the box, an actuating member connected with said presser yieldingly, and movable in the same direction, a spring for moving said actuating member outwardly, and operating means for moving said actuating member and the presser inwardly.

34. In a machine of the class described, a box-holding die having a body, a presser mounted on said body movably and adapted to engage a side of the box, a rod extending outwardly from the presser, parallel to its path, two collars on said rod, an actuating member having a sliding connection with said rod between said collars, a spring coiled on said rod between said actuating member and one of said collars, and means for operating said actuating member.

35. In a machine of the class described, a box-holding die having a body, a presser mounted on said body movably and adapted to engage a side of the box, a rod extending outwardly from the presser and movable therewith, two collars on said rod, an actuating member having a sliding connection with said rod between said collars, a spring coiled on said rod between said actuating member and one of said collars, a spring interposed between said body and said actuating member and tending to move said member outwardly, and operating means for moving said member inwardly.
36. In a machine of the class described, a box-holding die mounted movably, a folder mounted on said die movably, a normally stationary cam for operating said folder during the movement of the die, and means whereby both the folder and the cam may be adjusted to different distances from the path of the die.
37. In a machine of the class described, a movable box-holding die, comprising two parts movable in unison one of which is adjustable to different distances from the other transversely to the path of the die, a folder mounted movably on said adjustable part of the die, a normally stationary cam for operating said folder during the movement of the die, and means whereby both the die part
- carrying said movable folder, and the cam may be adjusted to different distances from the path of the other part of the die.
38. In a machine of the class described, a box-holding die comprising two parts movable in unison one of which is adjustable to different distances from the other, transversely to the path of the die, a folder past which said die moves in its travel, and means whereby both said part of the die and said folder may be adjusted to different distances from the path of the other part of the die.
39. In a machine of the class described, a box-holding die comprising two parts movable in unison, one of which is adjustable to different distances from the other, transversely to the path of the die, a cam carried by said adjustable part of the die, a folder past which said die moves in its travel, said folder being movably mounted on a stationary support and adapted to be moved toward or from the path of the die by the action of said cam, and means whereby both the die part carrying said cam, and said folder may be adjusted to different distances from the path of the other part of the die.

In testimony whereof we have signed this specification.

MARTIN FEYBUSCH.
PAUL W. FLEISCHER.
